US00D577708S

(12) **United States Design Patent**
von Meiss et al.

(10) **Patent No.:** US D577,708 S
(45) **Date of Patent:** ** Sep. 30, 2008

(54) **WIRELESS MICROPHONE TRANSMITTER**

(75) Inventors: **Basil von Meiss**, Zurich (CH); **Christian Harbeke**, Zurich (CH)

(73) Assignee: **Phonak AG**, Stäfa (CH)

(**) Term: **14 Years**

(21) Appl. No.: **29/302,741**

(22) Filed: **Jan. 23, 2008**

(51) **LOC (8) Cl.** 14-99

(52) **U.S. Cl.** D14/158

(58) **Field of Classification Search** D14/167, D14/154, 168, 188, 496, 156, 160, 161, 162, D14/163, 164, 165, 158, 341, 346, 342, 345, D14/155, 218, 225; D16/208; D26/38; 455/351, 455/350; D10/104, 106, 65

See application file for complete search history.

(57) **CLAIM**

The ornamental design for a wireless microphone transmitter, as shown and described.

DESCRIPTION

FIG. 1 is a perspective view of a first embodiment of a wireless microphone transmitter embodying our design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof;

FIG. 7 is a rear elevational view thereof;

FIG. 8 is a perspective view of a second embodiment of a wireless microphone transmitter embodying our design;

FIG. 9 is a top plan view thereof;

FIG. 10 is a bottom plan view thereof;

FIG. 11 is a right side elevational view thereof;

FIG. 12 is a left side elevational view thereof;

FIG. 13 is a front elevational view thereof; and,

FIG. 14 is a rear elevational view thereof.
